BRASSIÈRE AND CHEMISE.

Specification of Letters Patent. Patented Aug. 31, 1920.

Application filed September 27, 1919. Serial No. 326,857.

To all whom it may concern:

Be it known that I, RUTH B. OPPENHEIMER, a citizen of the United States, and a resident of the city of New Rochelle, 5 county of Westchester, and State of New York, have invented a new and useful Improvement in Combined Brassières and Chemises, of which the following is a specification.

10 The object of my invention is to provide an undergarment which will take the place heretofore occupied by two garments when bloomers are worn and be light and comfortable, economical and durable. This object is accomplished by my invention, one embodiment of which is hereinafter more particularly set forth.

15 For a more particular description of my invention, reference is to be had to the accompanying drawings, in which:

Fig. 2 shows the front of the top of the same.

25 Fig. 3 shows the means for securing the parts together at the top of the back.

Throughout the various views of the drawings, similar reference characters designate similar parts.

The garment 1 consists of a brassière 2 at 30 the top and a chemise 3 at the bottom. The former has straps 4 which may be made adjustable and seams 5 which may be unfinished so that the garment 1 may be sold otherwise complete and finished by the purchaser according to the fit desired. The parts 2 and 3 are connected by means of a suitable seam 6 and the back of the brassière 2 is closed by hooks and eyes 7 or any other suitable means. 35

40 The garment 1 may be fitted to the wearer and then worn with great comfort with bloomers.

Having thus described my invention, what I claim is:

45 A combined under garment which consists of a brassière with arm straps, a back opening and a bottom seam and a chemise secured to said brassière by said seam.

RUTH BLOCH OPPENHEIMER.
